UNITED STATES PATENT OFFICE

THEODORE R. TREIBER, OF CHICAGO, ILLINOIS, ASSIGNOR, BY MESNE ASSIGNMENTS,
TO THE BRUNSWICK-BALKE-COLLENDER COMPANY, A CORPORATION OF DELAWARE

BOWLING ALLEY

Application filed May 16, 1928. Serial No. 278,093.

My invention has for its main objects the provision of a bowling alley which is variably adjustable for leveling the bed of the alley, and which is preferably constructed largely 5 of metal, all with a view toward providing an alley of good playing qualities, economy in manufacture, ease of erection, solidity, comparatively great amount of salvage for reerection after taking it down, and leveling 10 without extensive planing of the upper or playing surface of the bed.

With these objects in view my invention consists in certain features of novelty in the construction, combination, and arrangement 15 of parts by which said objects and certain other objects, hereinafter appearing, are effected, all as fully described with reference to the accompanying drawings and more particularly pointed out in the appended claims.

20 In the said drawings—

Figure 1 is a partial and longitudinally condensed top plan view of a bowling alley embodying my invention.

Figure 2 is a partial and longitudinally condensed longitudinal vertical section on the line 2—2 of Figure 1.

Figure 3 is an enlarged partial side elevation of the alley with a part broken away and in section.

30 Figure 4 is a partial transverse section of the alley with a part broken away and in section.

Figure 5 is a perspective view of a pair of the clamp members used in the preferred 35 construction, hereinafter described.

Like characters of reference indicate like parts in the several views.

Referring to the drawings, 1 designates a 40 bowling alley bed which is constructed of suitable material such as wood, and which as shown and as usual is of non-sectional construction and consists of sleepers disposed in vertical planes and tongue and grooved and nailed together. See Figures 1 and 4.

45 A plurality of metal bed support members 2 underlie the bed and extend transversely thereof and are spaced at short intervals therealong. These support members 2 are of inverted U-shaped cross section and 50 have the intermediate portion of the section

thereof secured against the under surface of the bed by means of screws 3 passing through apertures thereof and screwthreaded into the bed, deadening material 4, such as felt, being preferably interposed between the support 55 members and the bed.

Each support member 2 is provided with a pair of metal support brackets 5 spaced therealong, and these brackets are of upright U-shaped cross section and have the legs thereof secured facewise against the legs of the section of the support member 2 as designated at 60 6. The support brackets 5 are thus horizontally disposed and the intermediate portions of the sections thereof extend horizontally 65 across between the legs of the sections of the support members 2 in spaced relation with the intermediate portions of the sections of the support members 2.

A pair of metal clamp members 7 is provided for each support bracket 5, and the clamp members of each pair thereof overlie respective of the upper and lower surfaces of a respective support bracket 5, deadening material 8, such as felt being interposed between 75 the clamp members and support brackets. See Figures 3, 4, and 5. The clamp members 7 extend outwardly beyond the support brackets 5, and vertically disposed metal support screws 9 pass through apertures through 80 the outwardly extending portions of respective pairs of clamp members. Metal nuts 11 are screwthreaded on the screws 9 above and below the pairs of clamp members 7 and serve to clamp the clamp members upon the deadening material 8 and the support brackets 5, a clamp member 7 of each pair being provided at the extreme outwardly extending end thereof with a lateral projection 12 engageable with the opposite clamp member to maintain the clamp members in substantially parallel clamping relation.

A pair of metal base members 13 of right angle section and spaced in a horizontal plane 85 extend longitudinally of the bed in underlying relation with the support members 2. These base members 13 have angles of the sections thereof secured downwardly upon a floor or foundation 14 in a suitable manner, as designated at 15 in Figure 4, and have the 100

other legs of the sections thereof projecting upwardly. The upright legs of the base members 13 have metal angle brackets 16 secured thereto at intervals therealong corresponding with the spacing of the screws 9, and the screws 9 pass through apertures therethrough, and metal nuts 17 are screw-threaded on the screws 9 and are disposed above and below the brackets 16 for adjustably positioning the screws 9 vertically with reference to the base members 13 and brackets 16. See Figures 3 and 4.

Thus it will be observed that the bed 1 may be variably adjusted throughout its length, 15 attention being directed to the fact that each adjustment device including a screw 9 is adapted for positively adjusting the respective support member 2 and the bed 1 both upwardly and downwardly.

In addition the clamp members 7 and related parts permit a slight lateral adjustment of the bed for aligning purposes, and provided admirably for the deadening material 8.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a bowling alley the combination with a plurality of metal bed support members of 35 angle section underlying the bed and secured therewith and extending transversely thereof and secured therewith and spaced longitudinally of the same and having angles thereof projecting downwardly, of a pair of metal 40 base members of right angle section and spaced in a horizontal plane and extending longitudinally of the bed in underlying relation with said support members and having legs thereof projecting upwardly, and a plurality of transversely spaced pairs of independent vertically disposed metal screw adjustment devices associated with the vertically projecting legs of said support and base members for adjustably supporting 45 respectively of said support members vertically from said base members and adapted for positively adjusting said support members both upwardly and downwardly.

2. In a bowling alley the combination with a horizontally disposed metal support member, of a pair of clamp members overlying respective of the upper and lower surfaces of said support member, and means 55 clamping said support member between said clamp members including a vertically disposed support screw.

3. In a bowling alley the combination with a horizontally disposed metal support member, of a pair of metal clamp members over-

lying respective of the upper and lower surfaces of said support member and extending outwardly beyond an edge of said support member in overlying relation, deadening material interposed between said clamp members and said support member, and metal means clamping said clamp members upon said deadening material and support member including a vertically disposed support screw associated with the outwardly extending portions of said clamp members.

4. In a bowling alley the combination with a horizontally disposed metal support member, of a pair of metal clamp members overlying respective of the upper and lower surfaces of said support member, metal means clamping said support member between said clamp members including a vertically disposed screw, a second support member, and means utilizing the thread of said screw for adjustably positioning said screw with reference to said second support.

5. In a bowling alley the combination with a horizontally disposed metal support member, of a pair of metal clamp members overlying respective of the upper and lower surfaces of said support member and extending outwardly beyond an edge of said support member in overlying relation, deadening material interposed between said clamp members and said support member, metal means associated with the outwardly extending portions of said clamp members for clamping said clamp members upon said deadening material and support member and including a vertically disposed screw, a second metal support member through which said screw extends, and a pair of metal nuts screw-threaded upon said screw and clamping said second support member therebetween for vertically adjusting said screw with reference to said second support member.

6. In a bowling alley the combination with a horizontally disposed metal bed support member of inverted U-shaped cross section, of a metal bracket secured with the legs of said section and extending across between the same in spaced relation with the intermediate portion of said section, of a pair of metal clamp members overlying respective of the upper and lower surfaces of said bracket between the legs of said section, and metal means clamping said bracket between said clamp members including a vertically disposed support screw.

7. In a bowling alley the combination with a horizontally disposed metal bed support member of inverted U-shaped cross section, of a horizontally disposed metal bracket of upright U-shaped cross section having the legs thereof secured facewise against the legs of said support member, a pair of metal clamp members overlying respective of the upper and lower surfaces of said bracket be-

tween the legs of said sections and extending outwardly beyond an end of said bracket in overlying relation, deadening material interposed between said clamp members and 5 said bracket, and metal means clamping said clamp members upon said deadening material and bracket including a vertically disposed support screw passing through apertures through the outwardly extending portions of said clamp members.

8. In a bowling alley the combination with a horizontally disposed metal bed support member underlying the bed of the alley and disposed transversely thereof, of a pair of 15 base members spaced in a horizontal plane and extending longitudinally of the bed in underlying relation with said support members, a pair of horizontally disposed metal brackets spaced along said support member, 20 two pairs of metal clamp members overlying respective of the upper and lower surfaces of respective of said brackets, metal means clamping said brackets between respective of said pairs of clamp members including 25 vertically disposed support screws, and a pair of metal means utilizing the thread of said screws for adjustably supporting said screws upon respective of said base members.

9. In a bowling alley the combination with 30 a horizontally disposed metal bed support member of inverted U-shaped cross section underlying the bed of the alley and secured therewith and disposed transversely thereof, of a pair of metal base members of right 35 angle section and spaced in horizontal plane and extending longitudinally of the bed in underlying relation with said support member and having legs thereof projecting upwardly, a pair of horizontally disposed metal 40 brackets of upright U-shaped cross section spaced along said support member and having the legs thereof secured facewise against the legs of said support member, two pairs of metal clamp members overlying 45 respective of the upper and lower surfaces of respective of said brackets and extending outwardly beyond ends of said brackets in overlying relation, deadening material interposed between said clamp 50 members and said brackets, metal means clamping said clamp members upon said deadening material and respective of said brackets including a pair of vertically 55 disposed support screws passing through apertures through the outwardly extending portions of respective pairs of said clamp members, a second pair of metal angle brackets secured on respective of the outwardly extending legs of said base members 60 and through vertical apertures of which respective of said screws pass, and pairs of metal nuts screwthreaded upon respective of said screws and clamping respective of said 65 second brackets therebetween for vertically

adjusting said screws with reference to said second pair of brackets.

In witness whereof I hereunto affix my signature this 12th day of May, 1928.

THEODORE R. TREIBER.
